UNITED STATES PATENT OFFICE

2,497,567

MOUNT STRUCTURE FOR ELECTRIC LAMPS

Joseph E. Stone, Cleveland Heights, Ohio, assignor to General Electric Company, a corporation of New York

Application April 27, 1949, Serial No. 90,013

5 Claims. (Cl. 176—39)

1

This invention relates to electric incandescent lamps in general, and more particularly to a mount construction therefor.

There are many so-called rough service applications where an electric incandescent lamp is subjected to considerable vibrations, jars or impacts, for instance in locomotive headlights, automatic mining machinery, earth moving equipment, tractors and other like equipment. In such cases, it is highly important that the filament or light source of the lamp be so supported that the forces developed by the vibrations or shocks be sufficiently dissipated in order to prevent distortion of the hot filament such as is apt to result in premature breakage or failure of the filament with consequent short lamp life.

It is an object of my invention therefore to provide an electric incandescent lamp having its filament so supported as to avoid detrimental effects of lamp vibration or impacts.

Another object of my invention is to provide an electric incandescent lamp having a flexible mount structure of simple form and which will effectively withstand vibration and impacts to which the lamp may be subjected in service.

Further objects and advantages of my invention will appear from the following description of a species thereof and from the accompanying drawing.

In the drawing, Fig. 1 is a sectional view of an electric incandescent lamp according to the invention; Fig. 2 is an enlarged perspective view of the lamp mount structure, with a portion thereof partly broken away to more clearly illustrate the invention; and Fig. 3 is an enlarged fragmentary view in section of a modified form of mount structure comprising my invention.

In accordance with the invention, the filament-supporting end or section of an electric incandescent lamp mount is rendered flexible in all directions by forming each of the lead-in wires or inleads, inwardly of the lamp envelope, in two individual sections and electrically and mechanically connecting them together in longitudinally aligned and separated end-to-end relation by a coil spring fitted over and bridging the gap between the separated ends of the two inlead sections and elastically gripping tightly the said inlead sections.

Referring to the drawing, the invention is there shown as applied to an electric incandescent lamp of the sealed beam type disclosed in U. S. Patent 2,148,314, D. K. Wright, and comprising a sealed glass envelope or bulb 1 consisting of preformed pressed glass reflector and cover glass 58

2

sections 2 and 3, respectively, sealed together at their peripheries by fusion, as indicated at 4. The inner surface 5 of the reflector section 2 is formed either of paraboloidal shape as shown, or of any other desired optical shape, and is provided with a reflecting coating 6 of aluminum, silver or other similar light-reflective material.

Mounted on the rear outer side of the reflector section 2 at the region of the apex or center thereof is a base structure 1 of the general type shown and described in U. S. Patent 2,272,512, Cotman, and comprising a pair of terminal contacts 8—8 in the form of metal straps or lugs which are suitably fastened, as by soldering for instance, to the close nipped ends 9 of respective metal ferrules or thimbles 10—10. The contact lugs 8—8 are provided with screw terminals 11—11 for connecting current supply wires thereto. The ferrules 10—10 are formed of a suitable metal which will readily "wet" and adhere to the glass of the reflector section 2 and they are provided with skirt portions 12 which are feathered to knife edges embedded and fused in the glass of the reflector section 2 around respective openings or passageways 13 through the wall thereof. The envelope 1 is provided with an exhaust tubulation 14 communicating with the interior of the envelope through an exhaust opening 15 in the envelope wall at the apex of the reflector section 2. After exhaustion of the envelope through the tubulation 14 and, if desired, introduction of a suitable gas filling such as nitrogen or argon, the tubulation 14 is sealed or tipped-off as indicated at 16.

Mounted within the envelope 1 and supported solely from the metal ferrules 10 in spaced relation to the envelope wall is a lamp mount structure 17 according to the invention and comprising a pair of lead-in conductors or inleads 18—18 secured at their outermost ends within the nipples 9 of the ferrules, as by solder 19 as shown. From the ferrules 10, the lead-in conductors 18 extend through the openings 13 in the wall of the reflector section 2 and into the envelope 1 in more or less parallel spaced relation and are connected at their innermost ends to the opposite ends of a filament 20 preferably in the form of a coiled wire of tungsten or other suitable refractory metal. In the specific case illustrated in Figs. 1 and 2, the filament 20 comprises a linear coil of tungsten wire having an opened center coil convolution 21 and extending transversely between the inner ends of the lead-in conductors 18 and mounted in the envelope 1 transversely of the axis of the reflecting surface 6 and approx-

imately centered at the focus thereof. The filament 20 is additionally supported in place by means of a supplementary support or anchor wire 22 which is formed at one end with a hook 23 within which the opened center convolution 21 is hooked. The other end of the filament anchor wire 22 is suitably fastened in place on an insulated part of the mount structure in a manner to be hereinafter described.

In accordance with the invention, the lead-in conductors or inleads 18-18 are each comprised of two separate wire sections 24 and 25 (i. e., an inner section 24 and an outer section 25) yieldingly held together in separated end-to-end relation and electrically connected by a coil spring or wire coil 26 fitted over and elastically gripping tightly the contiguous portions of the conductor sections 24, 25. The wire coils 26 are made of a material, such as tungsten, molybdenum or spring steel for instance, which will not lose its temper or springy character at the high temperatures encountered during operation of the lamp, and they are formed to an inside diameter slightly smaller (i. e., 2 or 3 thousandths of an inch) than the diameter of the wire conductor sections 24, 25 so that they cannot be slipped over the said conductor sections but can only be fitted thereover by screwing the wire coils thereonto. In such manner, a firm and tight elastic grip of the wire coils 26 on the wire conductor sections is provided whereby the two separated sections 24, 25 of each conductor 18 are firmly held together in spaced end-to-end relation and a good electrical connection formed between the separated conductor sections and their interconnecting wire coils. The portions 27 of the coil springs 26 bridging the gap between the separated conductor sections 24 and 25, being free to flex or bend in any direction because of the absence of any stiffener or filler member therein, therefore provide a yieldable connection between the conductor sections 24, 25 which serves to impart flexibility in substantially all directions (i. e., 360° solid angle) to the filament-supporting end of the mount 17 whereby any vibrations or shocks to which the lamp may be subjected in service are effectively absorbed or cushioned by such yieldable connecting sections 27.

The characteristics of the coil springs 26 employed and the spacing of the conductor sections 24, 25 are so selected as to support the filament 20 firmly in place in the envelope 1 while imparting the desired degree of flexibility to the upper section of the mount to absorb the vibrations and shocks incident to the normal usage of the lamp without causing undue filament movement and resultant wavering of the light beam emitted by the lamp. In the specific case illustrated, the individual wire sections 24 and 25 of the lead-in conductors 18 are made of approximately 50 mil diameter nickel wire and are separated end-to-end a distance of approximately 2 mm., while the wire coils 26 are made of approximately 15 mil tungsten wire coiled to an inside diameter of approximately 48 mils.

To maintain the points of support of the filament in fixed relation to each other at all times independent of any unitary movement thereof due to lamp vibration or shock, the inner sections 24 of the conductors 18 are rigidly tied together and held in proper relation by suitable insulative time means which, in the particular case shown, comprises a cross-bar or bridge 28 consisting of a short length of glass rod 29 having a pair of support wires 30 embedded in and projecting from

each of its ends. The cross-bar 28 is secured to the inner conductor sections 24 by suitably fastening each pair of its support wires 30, as by welding for instance, to the inner conductor sections 24 at spaced points therealong, as shown. The supplementary support or anchor wire 22 for the filament 20 is embedded and anchored in the glass rod 29 of the cross-bar, thus maintaining the intermediate support point for the filament in fixed relation to the end supports thereof at all times. The mount structure 17 according to the invention therefore includes as a part thereof a filament-supporting section or unit, comprising the inner conductor sections 24, the cross-bar 28 and the intermediate support wire 22, which holds the filament 20 in proper relation at all times and which is capable of moving as a unit, without relative movement between the filament and the adjacent supporting parts of the said unit, during vibration or other sudden movement of the lamp.

While the wire coils 26 are effectively prevented from moving or creeping along the conductor sections 24, 25 by reason of their tight elastic grip thereon, it is preferable to fixedly secure the said wire coils in place on the conductor sections. For this purpose, the wire coils 26 may be made of sufficient length to extend over substantially the full length of the outer conductor sections 25 so as to be embedded in the solder mass 19 which anchors the said outer conductor sections in the ferrules 10, thus holding the wire coils in place on the outer conductor sections. The inner ends of the wire coils 26 may be fastened in place on the inner conductor sections 24 by extending the said coils underneath at least the nearest ones of the support wires 30 of the insulating bridge or cross-bar 28 so as to be welded along with the said bridge support wires to the inner conductor sections.

Instead of employing coil springs of true helical form throughout their length as shown in Figs. 1 and 2, they may be provided with an intermediate portion 31 of greater flexibility than their other portions and located at and bridging the gap between the separated sections 24, 25 of the lead-in conductors 18, as shown in the modification of Fig. 3. These more flexible intermediate portions 31 of the coil springs may be constituted by an enlarged diameter coil portion such as shown in Fig. 3, or by an opened coil portion or other such varied shape coil portion. These enlarged diameter or other varied shaped intermediate coil portions 31 impart a greater degree of flexibility to the mount structure 17 and therefore may be used where such added flexibility is desirable. The modification of Fig. 3 also illustrates the application of the invention to the support of a modified form of filament 32 comprising a plurality of more or less side-by-side coiled sections 33 joined by loops or bights 34 and lying in a plane approximately coinciding with that of the inner conductor sections 24. The filament 32 is connected at its ends to the conductor sections 24 and is supported at the bights 34 by anchor wires 35 formed at one end with hooks 36 within which the filament bights 34 are hooked. The other ends of the anchor wires 36 are embedded in the glass insulating members 37 of upper and lower bridges or cross-bars 38 and 39, respectively, which are connected across the inner conductor sections 24 to rigidly tie them together.

From the foregoing it will be evident that the mount structure 17 comprising my invention provides a simple and effective flexible supporting

arrangement for the filament whereby any vibrations, jars or impacts to which the lamp may be subjected in service are readily absorbed by the yielding intermediate coil spring portions 27 or 31 of the lead-in conductors which act as an elastic connection or cushion between the inner or filament-supporting section of the mount and the anchored outer conductor sections 25 to effectively minimize distortion of the hot filament by such lamp vibrations or shocks, thus rendering the entire lamp structure especially useful for rough service applications such as a locomotive headlight or as a lighting unit for automatic mining or earth moving equipment, tractors and other similar equipment where the lamp is ordinarily subjected to unusual shock or vibration.

What I claim as new and desire to secure by Letters Patent of the United States is:

1. An electric lamp comprising an envelope, a filament in said envelope, lead-in conductors anchored to and supported from the wall of said envelope and extending into the envelope from their wall anchorages in spaced relation to the envelope wall, said conductors each comprising separate inner and outer sections spaced apart end-to-end and the filament being supported from and electrically connected to said inner sections, bridge means insulatively and rigidly tying the said inner conductor sections together, and a coil spring fitting over and gripping tightly the individual sections of each of said conductors and bridging the gap therebetween to yieldingly hold and electrically connect the said conductor sections together whereby to resiliently support the filament and inner conductor sections from the anchored outer conductor sections.

2. An electric lamp comprising an envelope, a filament in said envelope, lead-in conductors anchored to and supported from the wall of said envelope and extending into the envelope from their wall anchorages in the same general direction and in spaced relation to the envelope wall, said conductors each comprising separate inner and outer sections spaced apart end-to-end and the filament being supported from and electrically connected to said inner sections, bridge means insulatively and rigidly tying the said inner conductor sections together, and a coil spring fitting over and elastically gripping tightly the individual sections of each of said conductors and bridging the gap therebetween to yieldingly hold and electrically connect the said conductor sections together whereby to resiliently support the filament and inner conductor sections from the anchored outer conductor sections.
3. An electric lamp of the character set forth in claim 1 wherein the portions of the said coil springs bridging the gap between the separated conductor sections are of greater flexibility than the other portions thereof.
4. An electric lamp of the character set forth in claim 1 wherein the portions of the said coil springs bridging the gap between the separated conductor sections are of enlarged coil diameter.
5. An electric lamp of the character set forth in claim 1 wherein the coil springs are each fixedly secured to their respective inner and outer conductor sections.
